DESK AND CHAIR COMBINATION

Herbert W. Collins, London, Ky.

Application February 4, 1954, Serial No. 28,835

Term of patent 14 years

(Cl. D33—7)

FIG. 1

FIG. 2

FIG. 4

Fig. 1 of the drawing is a perspective view of a desk and chair combination showing my new design;

Figs. 2, 3 and 4 are top plan, front and end elevational views, respectively, of the desk and chair combination.

I claim:

The ornamental design for a desk and chair combination, as shown.
